Primary Examiner—Melody N. Brown*Attorney, Agent, or Firm*—Whyte Hirschboeck Dudek[57] **CLAIM**

The ornamental design for a van body, as shown and described.

DESCRIPTION

FIG. 1 is a front perspective view of a van body showing our new design;

FIG. 2 is a back perspective view; and,

FIG. 3 is a side elevation view taken from the left of FIG. 1, with the opposite side being a mirror image.

The broken lines shown in all figures are for illustrative purposes only and form no part of the claimed design.
